(57) **CLAIM**

The ornamental design for a gutter outlet, as shown and described.

DESCRIPTION

FIG. 1 is an isometric view from the upper right rear of a gutter outlet embodying my new design, shown as attached to the bottom of a gutter;

FIG. 2 is a front view of the gutter outlet shown in FIG. 1; FIG. 3 is a top view of the gutter outlet shown in FIG. 1 as seen from the front.

FIG. 4 is a top view of the gutter outlet shown in FIG. 1 as seen from the back.

FIG. 5 is a side view of the gutter outlet shown in FIG. 1; and, FIG. 6 is rear view of the gutter outlet shown in FIG. 1.

The broken lines shown in FIGS. 1 and 5 are for the purpose of illustrating environment and form no part of the claimed design.

1 Claim, 3 Drawing Sheets

FIG. 1

FIG. 3**FIG. 2****FIG. 4**
